UNITED STATES PATENT OFFICE

RICHARD WILLIAM FARMER, OF NORTHAMPTON, ENGLAND, ASSIGNOR TO UNITED SHOE MACHINERY CORPORATION, OF PATERSON, NEW JERSEY, A CORPORATION OF NEW JERSEY

METHOD OF AND MACHINE FOR MAKING SHOES

Application filed May 21, 1928, Serial No. 279,583, and in Great Britain June 13, 1927.

This invention relates to methods of and machines for making shoes, and is herein illustrated as embodied in a staple-fastening-inserting machine of the type disclosed in United States Letters Patent No. 1,059,984, granted April 29, 1912, on an application filed in the names of E. Erickson and J. W. Cosgrove.

In the manufacture of welt shoes the upper is usually lasted over the edge of the insole and temporarily secured in lasted position by tacks driven into the insole preferably in the angle between the feather of the insole and the shoulder against which the welt is sewed. Before the welt-attaching operation some or all of the lasting tacks are removed to prevent their interfering with the needle of the welt-attaching machine. However, in order to maintain the upper in final lasted position, it is customary to drive staples of fine wire through the upper into the rib of the insole permanently to secure the upper to the insole. This operation is commonly carried out by means of a staple-fastening-inserting machine of the type referred to, the operation being performed separately from and usually before the tack-pulling operation.

An object of the present invention is to eliminate in the manufacture of shoes the necessity for performing separate fastening-inserting and tack-pulling operations prior to attachment of the welt to the insole. To this end, one feature of the invention resides in the provision of an improved machine for inserting fastenings permanently to secure the upper to the insole of a shoe and having means for pulling out temporary fastenings which have previously been inserted into the shoe to hold the upper in lasted position. As illustrated, the machine comprises staple-inserting mechanism having associated therewith a tack-pulling tool operable concurrently with the staple-inserting mechanism to pull lasting tacks as fastenings are driven into the shoe, the operation being such that the upper is held in lasted position during the insertion of the staples and as the tacks are pulled. By the use of the construction described, when a shoe is presented to the machine to receive staple fastenings for permanently se-

curing the upper to the channel lip or rib of the insole, the lasting tacks are removed from the shoe, thus avoiding the necessity for performing a separate tack-pulling operation.

In its method aspect the invention resides in the provision of an improvement in methods of making shoes which consists in inserting staple fastenings in a shoe permanently to secure the upper to the rib of the insole and concurrently removing tacks previously inserted in the shoe to hold the upper in lasted position.

Other objects and features of the invention will appear from the following description and claims when considered in connection with the accompanying drawings, in which,

Fig. 1 is a side view, partly in section, of a portion of a tack-pulling and stapling machine embodying the invention; and

Fig. 2 is an angular perspective detail looking at the tack-pulling tool and the staple nozzle endwise and showing a shoe in operative relation thereto.

The construction and operation of various parts of the illustrated machine are like the construction and operation of corresponding parts of the staple-inserting machine illustrated in the aforementioned Letters Patent No. 1,059,984, to which reference may be had for detailed disclosure of the construction and arrangement of parts not fully disclosed herein.

The staple-forming and inserting mechanism comprises an outside former 10 arranged to slide in a guideway in the frame 12 of the machine head, the outside former carrying at its forward end a tongue 14 which projects in front of the former and engages the upper of a shoe just before a staple is inserted and is co-operable with an anvil hereinafter described to press together close to the line of insertion of the staples the upper and the sewing rib of the insole through which the staples are to be driven. The outside former 10 is provided upon its upper rear surface with rack teeth 16 which mesh with teeth 18 of a segment rack carried by a lever 20 fulcrumed upon a rock shaft 22 and having upon its other arm 24 a cam roll 26 which enters a cam groove 28 in a cam disk 30 carried by a drive

shaft 32. The outside former 10 co-operates to form a staple with an inside former 34 carried upon a vertical plunger 36 operatively connected to a lever 38 mounted on rock shaft 40. Wire is fed intermittently by mechanism to the staple formers 10 and 34 which operate to form staple fastenings which are driven by means of a driver 42 connected to a driver slide 44, the driver 42 operating to force staples one at a time through an opening 46, Fig. 2, in a staple nozzle 48. In order to clamp the work and to clinch the staples in the work after they are driven, opposite the end of the staple nozzle 48 is positioned an anvil 50 which is carried by a slide 52 in a forward extension 53 of the machine frame 12. The slide 52 is provided at its rear end with an upright portion 54 through which extends a bolt 56 having a forked extension 58 embracing a lever arm 60 upon the rock shaft 62, the arm 60 being adjustably connected at its end remote from the shaft to an extension 64 of the lever arm 24 by means of a link 66. The length of the link 66 can be regulated by adjustment of the 25 nut 67 thereby to regulate the stroke of the anvil 50. The construction and arrangement of parts are such that, as the driver 42 forces a staple through the upper and the sewing rib of the insole to secure them 30 together, the lever 60 operates the anvil 50 to move it toward the end of the staple nozzle 48, thus to clinch the ends of the staple after it has been inserted in the work. For a more detailed description of the construction and operation of the parts so far described, reference may be had to the aforementioned Letters Patent.

Closely associated with the fastening-inserting mechanism above described is tack-pulling mechanism arranged for operation in conjunction with the fastening-inserting mechanism. The tack-pulling mechanism, best shown in Fig. 2, comprises a bell-crank lever 68 carrying a substantially horizontal forwardly extending tool 70 the end of which is comparatively thin and flat and the forward edge of which extends adjacent to and substantially in line with the face of the end of the staple nozzle 48. The forward edge of the tool 70 has in it a series of notches 72 designed to engage lasting tacks in the work and to pull them when the lever 68 is operated. The lever 68 is pivoted on the shaft 62 and is oscillated on the shaft by the lever 20, the lever 68 being provided with a pin 74 positioned in a slot 75 in a link 76 adjustably connected to the extension 64 of the lever arm 24 of lever 20. The pin-and-slot connection provides for lost motion between the lever 68 and the link 76, thus permitting movement in a vertical plane of the tack-pulling tool 70 in locating it in operative position with respect to work presented to the nozzle 48. The frame 12 of the machine carries a lug 77 provided with a set-screw 78

for engaging with the lever 68 to limit the forward movement of said lever and consequently to limit the movement of the tack-pulling tool downwardly. For normally maintaining the tool in engagement with work presented to the nozzle 48, there is provided a spring 80 connected to a portion of the frame 12, the spring being operable to pull the tool 70 down against the upper of a shoe in operative position with respect to the nozzle 48.

Since the tack-pulling tool 70 is operatively connected to the lever 20 which operates the staple driver 42, the tool is rocked upon the shaft 62 simultaneously with an operation of the driver 42 so that a tack-pulling operation is performed at the same time that a staple is inserted in the work.

In the operation of the machine, a shoe is so presented to the mechanism that the upper of the shoe engages the staple nozzle 48 and the tack-pulling tool 70 rests upon that portion of the upper positioned between the feather of the insole and the shoulder against which the welt is sewed, and the shoe is moved by the operator from left to right (Fig. 2). As the shoe is moved across the face of the staple nozzle 48, successive staples are driven through the upper and the rib of the insole and clinched upon the anvil 50, thus securing the upper and insole together progressively, the staples being inserted in a line slightly above the path of movement of the needle in the welt-stitching operation, as shown at 82. Simultaneously with the operation of the fastening-inserting mechanism the tack-pulling tool 70 is oscillated about the shaft 62 in a counter-clockwise direction and the notched end of the tool 72 engages such lasting tacks as may be in position to the left of the staple nozzle 48 and operates to pull the tacks from the work. During the operations upon the work, the nozzle 48 prevents upward movement of the work under the action of the tool 70, and the anvil 50 prevents forward movement of the work due to the thrust of the tool 70 and the driver 42.

The operation of the tack-pulling tool is such that the tacks are removed automatically as the shoe is moved across the face of the staple-driving mechanism, thus permitting the operator to give substantially his entire attention to the location of the work with respect to staple-driving mechanism.

Having described my invention, what I claim as new and desire to secure by Letters Patent of the United States is:—

1. A fastening-inserting machine comprising continuously operating means for pulling fastenings from the work to be operated upon, and means for driving fastenings into the work located adjacent to the pulling means and operable at each operation of the pulling means.

2. A fastening-inserting machine compris-

ing means for driving fastenings into the work to be operated upon, continuously operating means adjacent to the driving means for pulling fastenings from the work, and means for causing the driving means and the pulling means to operate simultaneously with each other.

3. A machine for operating upon shoes having, in combination, a fastening-inserting device, a fastening-pulling tool located adjacent to the device, and means for operating the device and tool simultaneously to insert a fastening to secure the upper of a shoe to the rib of the insole and to pull a fastening from the shoe.

15 4. A machine for operating upon shoes comprising means for inserting staple fastenings in a shoe to secure the upper to the insole and means operable simultaneously with the fastening-inserting means for pulling fastenings which have previously been positioned in the shoe.

20 5. A fastening-inserting machine having, in combination, means for inserting fastenings progressively to secure the upper of a shoe to the rib of the insole and means operable simultaneously with the operation of the fastening-inserting mechanism for pulling lasting tacks positioned in the shoe.

25 6. A machine for operating upon shoes having means for driving fastenings through the upper of a shoe and the rib of the insole to secure together the upper and insole, a tack-pulling tool positioned adjacent to the driving means, and associated means for operating the driving means and tool.

30 7. A machine for operating upon shoes having means for driving staple fastenings through the upper of a shoe and the rib of the insole to secure together the upper and insole comprising a nozzle for the fastenings, a tack-pulling tool positioned adjacent to the nozzle, and means for simultaneously operating the driving means and tool.

35 8. A fastening-inserting machine comprising means for inserting staple fastenings in one portion of a shoe permanently to secure the upper to the rib of the insole, and means operable concurrently upon another portion of the shoe to remove temporary fastenings previously inserted in the shoe.

40 9. A machine for operating upon shoes comprising means for inserting staples in a shoe progressively to secure the upper of the shoe to the rib of the insole, means for clinching the staples, and means operable simultaneously with the clinching means for pulling temporary fastenings previously inserted in the shoe.

45 10. A machine for operating upon shoes comprising means for inserting wire staples in a shoe permanently to secure together the upper and the rib of the insole, and means operable upon an adjacent portion of the shoe

to remove lasting tacks previously inserted in the shoe.

11. That improvement in methods of making shoes which consists in inserting staple fastenings in a shoe progressively to 70 secure together the upper of the shoe and the rib of the insole and concurrently with the stapling operation removing temporary fastenings previously inserted in the shoe.

12. That improvement in methods of 75 making shoes which consists in inserting staple fastenings in a shoe permanently to secure the upper of the shoe to the rib of the insole and removing lasting tacks previously inserted in the shoe progressively as the 80 staple fastenings are inserted.

13. That improvement in methods of making shoes which comprises inserting staple fastenings in a shoe permanently to secure the upper of the shoe to the rib of the insole 85 and removing lasting tacks from one portion of the shoe as staple fastenings are inserted in another portion of the shoe.

14. That improvement in methods of making shoes which comprises inserting staple fastenings in a shoe permanently to secure the upper of the shoe to the rib of the insole and removing lasting tacks from one portion of the shoe as staple fastenings are inserted in an adjacent portion of the shoe. 90

15. That improvement in methods of operating upon shoes having uppers held in temporary lasted position by tacks, which consists in inserting staple fastenings in the shoe progressively to secure the upper of the shoe to the rib of the insole and concurrently removing tacks from adjacent portions of the shoe. 100

16. That improvement in methods of operating upon shoes in which the upper is held temporarily in lasted position by means of tacks, which consists in progressively inserting staple fastenings permanently to secure the upper of the shoe to the rib of the insole and concurrently removing the tacks from 110 the upper.

In testimony whereof I have signed my name to this specification.

RICHARD WILLIAM FARMER.
